UNITED STATES PATENT OFFICE.

JOHN DAVID KEITH AND WALTER EDGAR FAULKNER, OF SANTA ANNA,
TEXAS.

COLD-IRON STRAIGHTENER.

No. 853,513.

Specification of Letters Patent.

Patented May 14, 1907.

Application filed January 23, 1907. Serial No. 353,708.

To all whom it may concern:

Be it known that we, JOHN DAVID KEITH and WALTER EDGAR FAULKNER, citizens of the United States, residing at Santa Anna, in the county of Coleman and State of Texas, have invented a new and useful Cold-Iron Straightener, of which the following is a specification.

This invention relates to a straightening device of that type in which a draft hook and a relatively stationary hook are arranged on the body of the device with an adjustable arm mounted on the body so that wagon axles, shafts, pipes, and similar objects, can be straightened or bent, as desired, without having to be removed from their supports.

The invention has for one of its objects to simplify and improve the construction and operation of devices of this character so as to be comparatively easy and inexpensive to manufacture, readily manipulated, and capable of producing a powerful bending effect.

A further object of the invention is the provision of a device of the character described in which independently adjustable and interchangeable members are employed, whereby the device can be employed for straightening a shaft, or the like, when bent to either side of its normal position.

30 A further object of the invention is the employment of a draft hook which is adapted to be actuated longitudinally in either direction so as to restore a shaft, axle, pipe, or the like, to its normal position.

35 With these objects in view, and others, as will appear as the nature of the invention is better understood, the invention comprises the various novel features of construction and arrangement of parts, to be more fully described hereinafter, and set forth with particularity in the claims appended hereto.

In the accompanying drawing, which illustrates one of the embodiments of the invention, Figure 1 is a perspective view of the device showing one manner in which it can be operated. Fig. 2 is a front view showing a different manner of operation of the device.

Corresponding parts in the several figures are indicated throughout by similar characters of reference.

Referring to the drawing, 1 designates the bar-shaped body of the device, which is of substantially the same cross section throughout its length, except at one end where an eye 2

is formed. The body 1, as shown in the present instance, comprises a strip of metal of suitable cross section bent centrally on itself with its two halves in contact, the eye 2 being shaped at the middle of the metal strip or bar from which the body is made. Extending freely through the eye 2 is the threaded shank 3 of the draft hook 4. The shank 3 is of any desired length and engaging the thread thereof is a lever nut 5 and an ordinary wrench nut or bur 6, the latter being arranged on the under side of the body and the lever nut on the upper side. At the root of the hook 4 is formed a transverse shoulder or abutment 7 on which the article to be straightened is adapted to rest according to one method of using the device. On the body 1 is slidably mounted the fulcrum or arm 8 and the relatively stationary hook 9. This hook 9 and arm 8 are freely slideable longitudinally of the body 1 and are removable therefrom so that their positions may be reversed. The arm and hook are each provided with an angular opening 10 through which the body 1 extends.

In operating the device, in accordance with the method shown in Fig. 1, the arm 8 occupies a position between the two hooks of the device, and the lever nut 5 is employed for actuating the draft hook. The object to be straightened may be a pipe, shaft, axle, piece of bar metal, or the like. The object designated by 11 is engaged by the hooks 4 and 9, and the arm 8 is then adjusted to the proper position for producing the desired bending effect. In case the arm is not long enough to bear upon the object, a block of metal 12 may be inserted between its free end and the object, as shown. With the parts in this position, the draft hook 4 is ready for operation. The lever nut 5 is then turned in such a direction as to draw the hook 4 toward the body 1, the said nut 5 bearing against the top surface of the body at the eye 2. The arm 8 thus acts as a fulcrum on which the object is bent, while the hook 9 serves to steady the object. Before the nut 5 is operated, it is necessary to run the nut 6 back toward the hook 4 so as not to interfere with the movement of the latter by the turning of the nut 5.

In case it is desired to bend the object 11 in the direction opposite from that already described, the arm 8 and hook 9 are removed

from the body 1 and returned thereto in reverse order, as shown in Fig. 2. The device is then adjusted to the object 11 so that the latter bears against the abutment 7. After 5 the nut 5 is run back the desired distance, the nut 6 is turned so that the hook 4 is moved away from the body, the said nut 6 bearing against the underside of the eye 2. By thus 10 operating the nut 6, the object 11 is bent back to its normal position about the hook 9 as a fulcrum. The advantage in having the arm 8 and hook 9 interchangeable is that pipes, shafting, and the like, that are located in close quarters, can be straightened by 15 either of the methods described, while the device as a whole occupies the same position. As, for instance, where a pipe is located in the corner of a room, the same can be bent from one side or the other with equal facility 20 by means of the present device.

From the foregoing description, taken in connection with the accompanying drawing, the advantages of the construction and of the method of operation will be readily apparent 25 to those skilled in the art to which the invention appertains, and, while we have described the principle of operation of the invention, together with the apparatus which we now consider to be the best embodiment thereof, 30 we desire to have it understood that the apparatus shown is merely illustrative, and that various changes may be made, when desired, as are within the scope of the claims.

What is claimed is:—

35 1. In a metal straightener, the combination with a beam or body portion composed of a strip of flat metal bent centrally on itself to form an eye at one end of the beam and having its arms doubled and engaging one 40 another throughout their length to form a

guiding portion having an angular cross section of uniform dimensions, of a screw extending through said eye and having a hook thereon to engage the work, and means co-operating therewith and engaging the opposite edges of the beam for operating the screw axially in both directions, and a fulcrum arm and a resistance hook having angular openings therein of equal dimensions to interchangeably receive the beveled arm of the 45 beam and to permit disengagement and interchanging of the fulcrum arm and hook by a relatively longitudinal movement thereof. 50

2. In a device of the character described, the combination with a beam or body portion 55 having an angular cross section toward one end and an eye formed at the other end, of a screw fitted to operate in said eye and provided with suitable actuating means for moving it axially in two directions, a hook 60 rigidly fixed to said screw having a transverse abutment thereon adapted to co-operate with the work when the screw is being actuated in one direction, and having a curved portion opposite to said abutment to co-operate with 65 the work when the screw is being operated in the opposite direction, and interchangeable fulcrum and resistance devices guided on the beam and adapted to be arranged in reversed order when said screw is operated in opposite 70 directions.

In testimony that we claim the foregoing as our own, we have hereto affixed our signatures in the presence of two witnesses.

JOHN DAVID KEITH.
WALTER EDGAR FAULKNER.
